UNITED STATES PATENT OFFICE.

WARREN MACPHERSON, OF CAMBRIDGE, MASSACHUSETTS.

ELASTIC STEP-MAT.

1,398,701.

Specification of Letters Patent. Patented Nov. 29, 1921.

Application filed September 4, 1920. Serial No. 408,166.

To all whom it may concern:

Be it known that I, WARREN MACPHERSON, a citizen of the United States, residing at Cambridge, in the county of Middlesex 5 and State of Massachusetts, have invented new and useful Improvements in Elastic Step-Mats, of which the following is a specification.

This invention relates to a mat of elastic 10 material, such as flexible vulcanized rubber, or a vulcanizable composition containing rubber, and provided with ribs on its top surface, collectively constituting an anti-frictional tread. A mat of this character is 15 particularly useful on running-boards of automobiles.

The object of the invention is to provide a ribbed mat, adapted, when in use, to cause drainage of water between its ribs, from the 20 mid length to opposite ends of the mat.

The invention is embodied in the improvements which I will now proceed to describe and claim.

Of the accompanying drawings forming a 25 part of this specification,—

Figure 1 is a top plan view of a mat embodying the invention.

Fig. 2 is a section on line 2—2 of Fig. 1.

Fig. 3 is a section on line 3—3 of Fig. 1.

30 The same reference characters indicate the same parts in all of the figures.

In the drawings, 12 represents the body of my improved mat, having a flat bottom face, adapted to bear on the top surface of an 35 automobile running-board. Spaced apart longitudinal ribs 13 are molded on the top surface of the body, the upper faces of said ribs collectively constituting a tread for a boot or shoe sole. The ribs are spaced apart 40 by portions of the top surface of the body 12, and the top surface portions between the ribs are inclined, as shown by Fig. 2, from a point 14 at the mid length of the body to opposite ends of the body. The inclined 45 surface portions and the sides of the ribs constitute gutters extending from end to end of the body, the bottoms of said gutters being inclined as and for the purposes above stated.

The upper faces of the ribs 13 are preferably parallel with the bottom of the body 12, as shown by Fig. 2, so that the sides of the ribs are higher at the end portions than at the mid length portion of the mat, the top faces of the ribs, therefore, forming a flat 55 tread, which is not inclined like the portions of the top surfaces of the body between the ribs.

It will now be seen that provision is made for drainage of water from the top surface 60 of the mat. It will also be seen that by forming the top faces of the ribs 13 parallel with the bottom faces of the body 12, I provide substantially the same wear-resisting thickness at the end portions as at the mid 65 length portion 14 of the mat.

The body is preferably provided with orifices 15 to receive attaching screws.

I claim:

1. A step mat composed of an elastic body 70 having a flat bottom face and spaced apart ribs integral with the body and projecting above the top face of the latter, said ribs and top face forming gutters extending from end to end of the body, and having bottoms 75 which are inclined to permit water to flow from the mid-length to the opposite ends of the body between the ribs, the upper faces of said ribs collectively constituting an anti-frictional tread above the body. 80

2. A step mat composed of an elastic body having a flat bottom face and spaced apart ribs integral with the body and projecting above the top face of the latter, said ribs and top face forming gutters extending 85 from end to end of the body, and having bottoms which are inclined to permit water to flow from the mid-length to the opposite end of the body between the ribs, the upper faces of said ribs being substantially parallel with 90 the bottom face of the body and collectively constituting a flat antifrictional tread above the body.

In testimony whereof I have affixed my signature.

WARREN MACPHERSON.
